(57) **CLAIM**

The ornamental design for a mounting assembly for a satellite dish, as shown and described.

DESCRIPTION

FIG. 1 shows a front perspective view of a mounting assembly according to the present invention;

FIG. 2 shows a front elevation view of the mounting assembly;

FIG. 3 shows a rear elevation view of the mounting assembly;

FIG. 4 shows a right elevation view of the mounting assembly;

FIG. 5 shows a left elevation view of the mounting assembly;

FIG. 6 shows a top plan view of the mounting assembly;

FIG. 7 shows a bottom plan view of the mounting assembly;

and,

FIG. 8 shows a perspective view of the mounting assembly shown in a condition of use.

The broken lines illustrate portions of the mounting assembly for satellite dish. The broken lines showing a satellite dish in FIG. 8 illustrate environmental structure; all broken lines form no part of the claimed design.

1 Claim, 8 Drawing Sheets
